UNITED STATES PATENT OFFICE.

DAVID ANTHONY KEIZER, OF WINNIPEG, CANADA.

BRICK-MACHINE.

SPECIFICATION forming part of Letters Patent No. 686,659, dated November 12, 1901.

Application filed December 18, 1900. Serial No. 40,831. (No model.)

To all whom it may concern:

Be it known that I, DAVID ANTHONY KEIZER, of Winnipeg, Manitoba, Canada, have invented a new and useful Improvement in 5 Brick-Machines, of which the following is a specification.

My invention is in the nature of an improved form of brick-machines in which are embodied the elements of a series of molds 10 with compressing-dies linked together as an endless chain and provided with clay-mixing devices, packing devices for filling the molds, and pressing devices combined with a subjacent endless belt carrying detachable pallets or plates which are designed to receive 15 the bricks from the molds and carry them away.

My invention consists in the special construction and arrangement of these several 20 features and combination of parts, which will be hereinafter fully described with reference to the drawings, in which—

Figure 1 is a vertical side elevation, partly in section, of the entire machine. Fig. 2 is 25 an end elevation of the same looking from the left-hand side of Fig. 1. Figs. 3 and 3^a are vertical transverse sections taken on lines 3 3 3^a 3^a of Fig. 1 and shown on a somewhat larger scale. Fig. 4 is an isometric view of 30 one of the pressing-dies. Figs. 5 and 6 are respectively a side and a top view of one of the molds in which the dies play and which molds are linked together in a series forming an endless belt. Fig. 7 is a side view, partly 35 in section, of the mold-belt, its frame, and coacting parts. Fig. 8 is a side view of a portion of the subjacent pallet-belt that receives the bricks after they are molded in the mold-belt above. Figs. 9 and 10 are re- 40 spectively a cross-section and a longitudinal section, on an enlarged scale, of one of the joints of articulation of the pallet-belt which carries away the bricks.

Before proceeding to describe my invention in detail I would state that its construction generally comprises three separate pug-mills constructed as horizontal open troughs with hopper-shaped sides, as seen in Fig. 2. Two of these pug-mills or clay-mixers R² and 45 R³ are in alinement, while the third, R', is at right angles to the other two and between them. They all three feed into the vertical

clay-cylinder R, Fig. 1, where spiral blades pack the clay into the endless belt of molds passing in succession below it. After each 55 mold is thus filled it passes (see Fig. 7) below a clay-packing plunger Z⁴, working down into it from above, and then passes above a pressing-die M, working up through the mold from the under side and strongly compressing the 60 clay against a pressure-plate F³ above. Then as the endless belt of molds passes around the hexagonal distending pulleys at the end the bricks are forced out upon detachable pallets or plates M³ on a long subjacent belt, 65 as seen in Fig. 1, to which belt the pallets are supplied automatically from a pile on a table M⁵ shown on the right.

I will now describe the actuating mechanism and its gearing.

Z² is the main drive-shaft, which is best seen in Fig. 2. This shaft receives its power through a large pulley H, which is to be connected by a belt with any suitable source of power. The shaft Z² has on one side of the 75 machine a small rigid gear-wheel d, Figs. 1 and 2, which engages with a large gear-wheel h, that is fast upon a horizontal shaft Z, that has a series of cam projections on it, as seen in Figs. 1 and 7, that act upon adjustable 80 box-sections N N', which in turn act upon the dies M, Fig. 4, which play through the mold K, Figs. 5 and 6, and press the clay into a brick. The shaft Z also has fast upon it a gear-wheel C, Fig. 1, which is of equal size 85 with and meshes into a gear-wheel B on the shaft Q, which carries the hexagonal pulleys a'. These gears C and B turn the belt of molds which at the other end pass around hexagonal pulleys a on shaft P, as seen in 90 Fig. 7. The large gear-wheel h, Fig. 1, also meshes with and turns a small gear e on a shaft Z³, which has cams (see Figs. 3 and 7) working in the yokes of plunger Z⁴, and which plunger packs the clay into the molds after 95 it has been delivered from the clay-feeder and before being pressed.

On the shaft Z² there is fixed a bevel-gear U³, which meshes with a bevel-gear U (see Fig. 1) on the lower end of an inclined shaft 100 T, journaled in bearings in an inclined frame W, and bearing at its upper end a bevel-gear U', which meshes with a bevel-gear S², fixed on a vertical shaft S, which is support-

ed upon a table bearing on the top of a vertical clay-cylinder R. This shaft has its lower end suspended within the cylinder and bears a series of spiral propeller-blades S', which when rotated feed the clay down into the molds. Above the shaft S there is arranged a thrust-bearing V, which is carried on the upper end of an upright derrick-frame, and by bearing against the upper end of the said shaft resists the upward strain resulting from the feed of the propeller-blades. The clay-cylinder R is open at its bottom and closed at the top, and into its sides at the top there open the discharge ends of the three pug-mills.

At the lower side of the large gear-wheel h, Fig. 1, it meshes with a small gear-wheel h', Fig. 2, on a shaft G, which at its other end has a bevel-wheel g', that engages with a bevel-wheel g on a long shaft R⁵, Fig. 1, running lengthwise the machine and parallel with it. This shaft at the back end of the machine bears a large band-wheel R⁶, which through a belt R⁹ turns a pulley-wheel R¹⁰ and through a series of gears R¹¹ turns a horizontal shaft R¹², which is armed with stirring-blades and which mixes the clay to a homogeneous consistency and discharges it at the open end of the trough into the upper end of the clay-cylinder R. On the forward end of the long shaft R⁵, Fig. 1, is fixed another bevel-wheel g², that engages with a bevel-wheel g³ on the end of a cross-shaft g⁴, which bears the sprocket-wheel J P, Fig. 8, which 35 distends one end of the pallet-bearing belt that receives the molded bricks.

To work the stirring-shaft of the pug-mill R², (see Fig. 2,) a pulley R²⁰ is connected by a belt R¹⁹ to a large pulley Z⁵ on the end of shaft Z², and to work the shaft of pug-mill R³ a pulley R³⁰ is connected by a belt R²⁹ to a large pulley Z⁴, fixed on the opposite end of the main drive-shaft Z². On the shaft Z², at one side of the pressing devices, Figs. 1 and 45 2, is fixed another band-pulley Z⁸, which is connected by a belt r, to a smaller pulley r', having a broad face, and this pulley r' is in turn connected by a belt r³ to a large pulley y² on a shaft y', which bears a rotary brush y, Fig. 1, which is arranged transversely to the mold-belt at the end of the same and is designed to brush off the faces of the dies in the molds K, which dies at this point of travel of the belt are brought up flush with the face of the mold. The mold-belt, Figs. 1, 3, and 7, is arranged within a frame composed of side pieces F and F² and a powerful horizontal deck-piece F³, resting on F², which rests upon intermediate deck-piece N², having V-tracks upon which the molds slide. The V's on hexagonal pulleys a' a' are continuations of the V's on N². The deck-piece F³ is firmly bolted to the base-piece F' by means of rods F⁴ F⁴.

65 F⁵ is a rear deck-piece resting on sides F², and F⁶, Fig. 3, represents the lower track parts

of the frame-pieces F F on which the mold-belt moves.

The special construction of the pallet-belt, which receives the bricks, is seen in Figs. 8, 9, and 10. J is a wheel between the links J' J' of the pallet-belt, which runs on a subjacent track J², and J³ J⁴ J⁵, Fig. 1, represents a wooden frame for supporting the same. M³, Fig. 10, represents detachable wooden pallets or plates, which are seated between lugs at the ends of links J'. M⁴ represents transverse shafts, which connect the carrier-links together and form axles for wheels. M⁵ (seen on the right of Fig. 1) is the pallet-table, on which the pallets M³ are stacked up in a pile and from which they are automatically fed to the belt or carrier, the lugs of the latter dragging the lowest pallet from the pile and carrying it under the inverted molds, which drop 85 the bricks thereon.

The brick-mold (see Figs. 4, 5, and 6) consists of a hollow box K, having compartments in which work vertically the pressing-dies M, each of which has at the end a projecting lug L, which protrudes through a slot L² on the end of the mold K. These lugs act as guides and prevent the binding of the dies. At the upper edge of each mold at each end there is a groove K⁶, into which lies a permanent 95 guide formed on the deck-pieces, (see Fig. 3,) which prevents the clay from being forced between the joints made by F³ and the tops of the mold during the pressing action. The die M, as shown, is cast in one piece, and is 100 shaped into six brick faces, whose dividing-spaces fit the division-plates of the mold K. The full action of die M in mold K is limited to the movement of the lugs L in the slots made in both ends of each mold. When on 105 the upper tracks, the dies may be adjusted by means of simple guide-rails placed on the lower deck N² and under the lugs L, so as to raise the dies in the molds to any desired thickness of brick, and also the exact amount 110 of clay is delivered into the mold to suit the supplementary top press or plunger Z⁴ and the powerful upward movement of the boxes N N' when lifted by cams on shaft Z.

N, Fig. 7, is a cast-iron retaining-box working vertically in a guiding-space in the deck N² and having a ridge on its lower side, against which the cams of shaft Z act to lift it. Block N' fits in N, and spacing-plates are to be laid between N and N' of greater or less thickness 120 to suit the thickness of the brick to be made. The block N' extends entirely across the machine, but is a little shorter than the top of die M, giving an equal lift against M throughout its length.

K², Fig. 1, is a revolving sieve or bolt for sifting dust down the casing k² onto the dies for preventing adhesion of the clay. This rotary sieve is on the same shaft with and is turned by the pulley r'.

One part of my invention relates to the combined mold and die K M, either singular or

plurally joined—that is, one or more brick may be made by it—and the same as a unit is joined to other units in an endless chain of molds by means of short bolts, which couple the same together. The endless chain of molds is supported by upper V-tracks on deck N², forming part of the frame of the brick-machine, and lower plain ones F⁶, Fig. 3, and is set in motion by hexagonal wheels a', whose perimeters are V-shaped. The belt of molds passing under the feed-cylinder receives therefrom the clay, which is forcibly screwed into the molds by means of the spiral blades, and to further assure the filling a top presser or plunger Z⁴, Fig. 7, has been added, which forces out the air and further solidifies the brick. Passing these points the molds pass under a strong underpolished deck-piece F³, having perforations or vents which allow surplus clay and air in molds to escape. When in this position, die M is forced upward by means of cam-shaft Z and adjustable compression-blocks N' N, which move in a slot in deck-piece N². Passing the latter point the molds are carried, by means of hexagonal wheels a' a', to an inverted position onto the lower tracks F⁶, where the bricks are pushed onto the pallets M³, passing thereunder. Expelling-guides are provided which bear downward against the lugs L of each inverted die as it passes over the point of discharge, forcing bricks onto pallets. Guides are also provided to raise the dies from the point of departure from hexagonal wheels a onto the upper V-tracks, which regulate the quantity of clay forced into the molds as they pass under the filling device. As each mold passes upward over the hexagonal wheels a revolving brush y cleans the faces of the top of each mold and die, and when the latter has reached a point just in front of the feed-cylinder the die is dusted with fine dry clay by means of revolving sieve K², Figs. 1 and 2, having a fine mesh, which dust prevents the moist clay sticking to the dies, thereby facilitating the discharge of bricks from the dies to which the clay would otherwise adhere. The inverted top faces of the dies fall flush with the top edges of the molds, and in this position they rise to the revolving cleaning-brush.

The second part of my invention relates to the brick-conveyer or pallet-carrier, on rollers and tracks, which works in unison with the endless belt of molds and is actuated by the same power. The said conveyer may be of any length, having at its farthest extremity from the machine similar sprockets to those shown in Fig. 8 and supported by rails fixed in a wooden frame.

The object of providing my brick-machine with three pug-mills is that as the bricks are molded so rapidly it became necessary to employ additional means for supplying the clay to it.

My brick-machine may be operated by steam, electric, or water power.

Having thus described my invention, what

I claim as new, and desire to secure by Letters Patent, is—

1. In a brick-machine, the combination with an endless series of molds having compressing-dies in their lower portions, a vertical feed-shaft with spiral blades on it arranged above the mold, a preliminary packing-plunger arranged above the mold and having a horizontal actuating-shaft with cams and upwardly-moving pressure-blocks arranged below the molds to act against the dies, and a horizontal actuating-shaft for said blocks having lifting-cam surfaces on the same for raising the blocks substantially as described.

2. In a brick-machine, the combination with an endless series of molds with feeding, packing, and pressing devices; of three pug-mills constructed with revolving shafts having stirring-arms said pug-mills being arranged at right angles to each other to deliver their clay into the top of the feeding-cylinder substantially as described.

3. In a brick-machine, a brick-receiving belt composed of jointed links each having two lugs on its upper face, one at each end forming a seat between them, combined with detachable plates or pallets for the bricks said plates being made of a width equal to the space between the lugs and fitting therein substantially as and for the purpose described.

4. In a brick-machine, a brick-receiving belt composed of jointed side links with lugs at their ends on their upper faces, detachable plates or pallets fitting between said lugs, cross-shafts connecting the links and forming articulated joints, and running wheels arranged on said shafts between the adjacent ends of the connected links on each side substantially as described.

5. In a brick-machine, the combination with an endless articulated belt of molds having movable dies in their bottoms; of a rotary brush arranged at the end of the belt about midway between the upper and lower sections to act upon the face of the die while it is vertical and still flush with the top of the mold as it rises from an inverted position substantially as described.

6. In a brick-machine, the combination of a chain of hollow box-molds having grooves at their ends parallel to their line of travel, stationary track-guides entering said grooves and pressing-dies rising and falling in said molds substantially as and for the purpose described.

7. In a brick-machine having a series of articulated molds forming an endless belt, the combination of the pressure-plate F³, the molds passing beneath it, and the dies operating through the molds upwardly, the said molds and pressure-plate having at their ends a tongue-and-grooved joint K⁵ to prevent the clay from oozing out the ends at this point substantially as described.

8. In a brick-machine having a series of articulated molds forming an endless belt, the

combination of the perforated pressure-plate F³, the mold K with division-plates and tongue-and-grooved joints at the ends on the top and bottom, and also end slots, and the die M having multiple brick faces separated by spaces fitting the division-plates, and also end lugs protruding through the end slots of the mold substantially as described.

9. The combination of the pressure-plate F³, a chain of molds with pressing-dies working in the same, a base-frame with tie-rods F⁴F⁴ securing the base-frame to the pressure-plate, a vertically-sliding block arranged in guides to operate against the lower side of the dies successively, and a horizontal cam-shaft

arranged beneath said block and adapted to lift the same substantially as described.

10. A brick-machine comprising three pug-mills arranged at right angles as described, an endless chain of molds having multiple compartments and corresponding multiple die-faces cast in one piece, pressure devices for operating the dies and mechanism connecting the working parts substantially as shown and described.

November 28, 1900.

DAVID ANTHONY KEIZER.
